HACKSAW MACHINE

George Swain and William Leslie Bower, Sheffield, England, assignors to James Neill & Company (Sheffield) Limited, Sheffield, England

Application November 16, 1938, Serial No. 240,866
In Great Britain November 30, 1937

16 Claims. (Cl. 29—73)

This invention relates to hack-saw machines. The main object of the invention is to provide a hack-saw machine in which the hack-saw blade is supported approximately opposite to the work and between its anchorages so that the blade is, at least in part, relieved of bending in its own plane.

A further object is the provision of a guide support against which the back of the blade slides in operation.

Another object is the application of at least the main part of the force required to feed the blade to the work, not as heretofore to the ends of the blade through the blade anchorages, but to the mid part of the blade substantially opposite to the work.

A further object is the provision of lateral support for the sides of the blade whereby the blade is prevented from bending or chattering perpendicularly to its own plane.

A further object is the provision of a machine in which each successive tooth is caused to remove its own quantum of material during the working stroke, the successive teeth being constrained to follow each other during the working stroke along parallel paths successively deeper in the work.

A further object is the provision of a machine in which an effective positive feed of the successive teeth each through a pre-determined distance into the work takes place during each working stroke.

A further object is the provision of an irreversible feed step near the beginning of each working stroke followed by an effective positive feed of the successive teeth each through a pre-determined distance into the work during the working stroke.

A further object is the limitation of the force applied in the irreversible feed step at the commencement of the working stroke.

Another object is the provision of a hack-saw adapted for use in the machine and to pre-determine, in the manufacture of the hack-saw, the distance through which the successive teeth of the saw are positively fed into the work during each working stroke.

According to the invention, the back of the hack-saw blade bears against and reciprocates relatively to a guide-support, which may be of less width than the saw set, located opposite the work and adapted, during the working stroke, to support the saw blade against any tendency to bend in its own plane. The guide-support is preferably rigidly connected to feed mechanism,

so that the force required to feed the blade to the work is applied, not as heretofore to the ends of the blade through the blade anchorages, but to the mid part of the blade substantially opposite to the work.

Lateral guides for the saw may also be provided, adapted to bear against the sides of the saw blade nearer the back than, and clear of, the saw teeth, these lateral guides being situated adjacent the work and being adapted to support the saw blade against lateral stresses in a direction at right angles to its own plane.

The guide support and saw are preferably fed or advanced towards the work by a substantially irreversible mechanism.

Although the guide-support and saw may be gradually advanced throughout the working stroke of the saw, in which case the pitch line of the saw teeth may be parallel to the direction of reciprocation of the saw, it is preferred to feed the guide-support and saw irreversibly in a step at about the end of the idle stroke and beginning of the working stroke and to dispose the pitch line of the saw teeth at an inclination to the direction of reciprocation. Preferably means are provided for limiting the force applied to the irreversible feed mechanism which may comprise a screw and nut relatively rotated by torque applied through a friction clutch in steps each of which terminates after the commencement of the working stroke. Since the feed mechanism is irreversible, the amount of feed and depth of cut during the working stroke are pre-determined by the amount of revolution of the clutch before slip takes place and, after the feed operation has been completed, the loading of the saw or the force applied in the feed direction is the dependent variable, instead of being, as in prior hack-saw machines, the independent variable; the independent variable throughout the remainder of the working stroke is, in the case of the invention, the effective distance of feed due to the inclination of the pitch line of the saw teeth to the direction of reciprocation. Thus the saw teeth are positively fed and are constrained to move in straight parallel lines during the working stroke so that each successive tooth may remove substantially the same depth of material and the total depth cut by each working stroke may be pre-determined by the angle of inclination of the teeth pitch line to the reciprocation line and by the distance through which the guide-support and saw are advanced towards the work at each feed step. For use in this manner the hack-saw may have the pitch line of its teeth inclined to

the back of the saw, the back being finished smooth, preferably being ground and, if desired, polished, to reduce friction with its guide-support which may be similarly treated.

The accompanying drawings illustrate, partly diagrammatically, one embodiment of hack-saw machine in accordance with the invention. In the drawings:

Figure 1 is a side elevation.

Figure 2 is an elevation of part of the machine on an enlarged scale showing the guide-support, 10

Figure 3 is a section on the line 3-3 of Figure 2,

Figure 4 is a vertical section in a plane at right angles to and on the line 4-4 of Figure 1 15 of part of the feed mechanism,

Figure 5 is an elevation partly broken away to show the interior in the direction of the arrows 5 of Figure 4,

Figure 6 is a bastard horizontal section on the line 6-6 of Figures 4 and 5, and

Figure 7 is a horizontal section on the line 7-7 of Figures 4 and 5.

Like reference numerals indicate like parts, where applicable, throughout the several figures of the drawings.

Referring now particularly to Figure 1 the hacksaw machine comprises a base 10 upon which is carried a main frame 11 supporting a work holder in the form of a vise having jaws 12 and an actuating handle 13. The main frame 11 also carries rollers 14 supported by brackets 15 and adapted to support the work and enable it to be easily traversed across the main frame 11. The saw bow 16 is carried in guides, the construction of which is shown particularly in Figure 3 in a pivoted feed arm 17 so that the saw bow has freedom to move in both dimensions in a plane. The feed arm 17 is connected by links 18 to a feed mechanism 19 by means of which the feed arm 17, and together with it the saw bow 16, may be fed downwards towards the work. The hack-saw blade 24 is carried between anchorages located at the ends of the saw bow 16.

As best shown in Figures 2 and 3 a guide-support 18 for the back of the saw blade is carried upon brackets or lugs 19 depending from a plate 20 extending over part of the length of the lower surface of the feed arm 17. The guide-support 18 is located by dowels 21 and clamped by means of clamping plates 19a and bolts 22 to the brackets or lugs 19 and the plate 20 from which these brackets or lugs extend is bolted to the feed arm 17 by bolts 23.

The guide-support 18 is of approximately the same width as the back of the hack-saw blade 24 which is clamped in the anchorages of the saw bow 16, this width being less than the saw set so that the guide-support 18 may follow the saw through the material being cut. The length of the guide-support 18 is approximately equal to the maximum width of material which the machine is designed to cut, the position of the guide-support on the feed arm 17 being such that it is opposite, immediately above in the construction illustrated, those teeth of the saw 24 which are in operative position in regard to the work.

The lower edge 28 of the guide-support is straight and smooth, being preferably ground and polished and the back of the saw blade 24 may be similarly finished.

The lugs 19 and plates 19a extend beyond the lower edge 28 of the guide support 18 to embrace the saw blade 24 to form pairs of lateral guides

but do not extend to the edge of the saw blade, the set teeth of the saw blade 24 projecting beyond the ends of the lugs 19 and plates 19a. The lugs 19, which may be of cast iron, may be provided with replaceable bearing pieces or fillets 25 as shown in Figure 3. The fillets 25 may be located by dowels 26 and clamped by bolts 27. The replaceable fillets are not required for the lower ends of the plates 19a as these plates may be of suitable bearing material and, being small and detachable, may be replaced when desired.

The lower edge 28 of the guide-support 18 bears against the back of the saw blade 24 and prevents any flexing of the saw blade in its own plane. The saw blade 24 is laterally guided between the pairs of lateral guides provided by the plates 19a and the fillets 25 which are located on opposite sides of the work. Flexing and chattering of the saw blade 24 in a direction at right angles to its own plane are thus prevented.

The lower edge 28 of the guide support 18 is, in the embodiment shown, parallel with the line of the guides upon which the saw bow 16 runs in the feed arm 17. The pitch line 29 (Figure 2) of the teeth of the saw blade 24 is inclined to the back of the saw blade at a small angle, the apex of the angle between the line 29 and the back of the saw blade being beyond the end of the saw which leads in the cutting direction. Thus, as the saw bow 16 is reciprocated relative to the feed arm 17 in a straight line, the saw blade 24 is reciprocated in a straight line along one dimension in a plane with the pitch line of its cutting teeth 29 oblique to that straight line in such a manner that the tooth leading in the cutting direction traverses a straight path at a higher level and the tooth following at a lower level throughout the stroke. The saw blade 24 follows a path in the plane which is at an inclination to the line of the cutting teeth 29, the motion of the blade having a component along the line of the cutting teeth and a component at right angles thereto. The prolongation of the path of the blade in the working direction diverges from the line of the cutting teeth 29 towards the work holder, whereby an effective positive feed of successive teeth 29 towards the work is secured. Thus each tooth follows the preceding tooth at a slightly greater depth in relation to the work and so tends to remove its own individual contribution of material.

Since the saw blade is mounted in the machine with its back parallel with the line of the guides upon which the saw bow 16 is reciprocated, it will be appreciated that the distance through which the successive teeth of the saw are positively fed into the work during each working stroke is pre-determined by the inclination of the line 29 of the teeth of the saw blade to its back.

In the embodiment of the invention shown in the drawings the feed arm 17, and with it the guide-support 18, the saw bow 16 and saw blade 24, are not loaded by some pre-determined force as in prior hack-saw machines but are together irreversibly fed towards the work a certain distance at the commencement of every cutting stroke. In prior hack-saws the loading or force in the feed direction applied to the saw bow is the independent variable. In contrast the hack-saw machine shown in the drawings operates with the distance of feed or depth of cut as the independent variable, the feed load or force being the dependent variable.

This is achieved by a feed mechanism 119 shown in detail in Figures 4, 5, 6 and 7 of the drawings.

Referring to these figures, the links 118 are trunnioned to the feed arm 17 and are connected at their other ends to a gear box 30. A right-handed main feed screw 31 is journalled with end thrust bearings in the gear box 30 so that any thrust or tension applied to the feed screw 31 is transmitted through the gear box 30 to the links 118 and the feed arm 17. The gear box 10 houses a bevel wheel 32 which is keyed to the end of the feed screw 31 and engages a bevel wheel 33 which is journalled upon a spindle 34 rigidly secured in the gear box 30. The bevel wheel 33 is splined or dogged to a handle 35 which is rotatable upon the spindle 34 and also movable axially thereon without dis-engagement from the bevel wheel 33. The handle 35 is provided with dogs 36 adapted to engage corresponding dogs on a collar 37 secured to the spindle 34. A spring 38 urges the handle 35 to one extreme position in which its dogs 36 are engaged with those of the collar 37 so that the handle 35 is located against rotation. With the handle 35 so located the screw 31 cannot be rotated. On the other hand the handle may be moved against the spring 38 to a position in which the dogs 36 are dis-engaged from those of the collar 37, when the handle may be rotated to cause 30 rotation of the screw 31.

The screw 31 engages a nut 80. This nut has a collar 39 which bears against a shoulder of a screwed sleeve 40 through ball-bearings, the nut and sleeve being axially located relative to one another by an end thrust bearing 41. The screwed sleeve 40 is located in a screw-threaded aperture of a housing 42 which is carried by trunnions in brackets 43 (Figure 1) supported upon the base 10 of the machine. The screw of the sleeve 40 is left-handed. The screw 31 and nut 80 form an irreversible screw and nut mechanism.

A transverse rock shaft 45 is journalled in the housing 42 and is oscillated by means of a crank 46, connecting rod 47 and a lever 48 which is mounted upon a journal on the machine frame 11 (see Figure 1). The other end of the lever 48 carries a roller 49 which bears against a cam 50 carried by the main crank shaft 51 of the machine which drives the saw bow through a connecting rod 52. The lever 48 may be biased by a spring 53 to maintain the roller 49 in contact with the cam 50. The rock shaft 45 is provided with an arm 54. The arm 54 lies between a lug 55 depending from a collar 56 of the screwed sleeve 40 and a lug 57 projecting from a clutch plate 58 embracing the nut 80. The clutch plate 58 is frictionally coupled to the nut 80 by means of friction linings 59 which bear against the collar 39 and a slideable collar 60 which is splined to the nut 80 and urged to close the friction clutch by a spring 61.

The collar 56 has a single tooth 62 which engages a slot in a spring-loaded plunger 63. The plunger 63 is loaded by a spring 64 bearing against an internal shoulder of an adjustable nut 65. The end of the plunger 63 projects beyond the internal shoulder of the nut 65 and is provided with a head in the form of a nut 66. By adjustment of the nut 65 the movement of the plunger 63 to the left and consequently the return movement in an anti-clockwise direction in Figure 6 of the nut 40, following the movement of the arm 54, may be adjusted.

The clutch plate 58 is similarly equipped with a tooth 70 engaging a slot in a spring-loaded plunger 71 governed by a nut 72 in a similar manner.

Furthermore a pawl 75 loaded by a leaf spring 76 is provided in the housing 42 to engage a ratchet 78 formed upon the outer surface of the collar 60 which is splined to the nut 80. The pawl 75 and ratchet 78 thus prevent rotation of the nut 80 in the clockwise direction in Figure 6 during the return stroke of the clutch plate 58 under the bias of the spring loaded plunger 71 and also the pawl 75 and ratchet 78 ensure the irreversibility of the screw and nut mechanism.

In operation, if it be assumed that the machine is just about to commence a cutting stroke and is in the position shown in Figure 1, the parts of the feed mechanism will be substantially in 20 the positions shown in the drawings. As the cutting stroke commences the lever 48 is permitted by the cam 50 to rotate under the bias of the spring 53 in a clockwise direction thus rotating the rock shaft 45 in an anti-clockwise direction in Figure 1. This anti-clockwise rotation of the shaft 45 in Figure 1 causes a clockwise movement of the shaft in reference to Figure 5 and thus causes the arm 54 to rotate the clutch plate 58 by engagement with the lug 57. Rotation of the clutch plate 58 takes place in an anti-clockwise direction referring to Figures 6 and 7. This rotation is transmitted to the nut 80 whereby the feed screw 31 is lowered until the teeth of the saw blade 24 are brought into 35 contact with the work and forced into the work with some force which is dependent upon the slippage of the clutch. The feed screw 31 is then held in this position throughout the remainder of the cutting stroke of the machine by the pawl 75 and ratchet 78. The cutting stroke proceeds until, near the end of the cutting stroke, the rock shaft 45 is rotated in the reverse direction by the cam 50, thus permitting the clutch plate 58 to reverse its rotation and to be restored to its 40 normal position by the spring biased plunger 71.

This reverse rotation of the rock shaft causes the arm 54 to engage the lug 55 thereby to rotate the screwed sleeve 40 through some predetermined angle. Rotation of the screwed sleeve 40 within the housing 42 causes that sleeve to be raised and with it the nut 80, feed screw 31 and feed arm 17, so that the saw blade 24 is raised out of contact with the work. During the return inoperative stroke the saw is maintained out of contact with the work. Near the end of the return stroke the cam 50 again permits the lever 48 to rotate in a clockwise direction in Figure 1, thus again rotating the rock shaft 45 and arm 54 in a clockwise direction in Figure 5. The screwed sleeve 40 is then rotated under the bias of the plunger 63 in an anti-clockwise direction in Figure 6, its lug 55 following the arm 54. The feed arm 17 is thus lowered to or near to the position to which it had been at the end of the preceding cutting stroke. The arm 54 then contacts with the lug 57 of the clutch plate 58 again to rotate the clutch plate 58 to lower the feed screw 31 and the cycle of operations is repeated.

Over-loading of the saw is prevented by slipping of the clutch which may be adjusted by adjusting the spring 64 and the adjustment of the maximum permitted feed per stroke is effected by the adjustment of the nut 72 which varies the position, in relation to the housing 42,

of its internal shoulder with which the head on the plunger 71 makes contact to limit the clockwise rotation of the clutch plate 58 (in Figure 7) when the lug 57 is following the return movement of the arm 54. Hence the position of the clutch plate 58 at the beginning of its feed movement and consequently the maximum permitted feed per stroke may be adjusted.

The feed arm may be moved towards and away from the work by pushing in the handle 35 to dis-engage its dogs 36 from those of the collar 37 and rotating the handle to cause rotation of the screw 31. Rotation of the screw 31, causes it to be raised or lowered relative to the nut 80.

It will be appreciated that one particular construction of hack-saw machine in accordance with the invention has been described and shown in the accompanying drawings and that many modifications may be made without departing from the scope of the invention.

What we claim is:

1. A hack-saw machine comprising saw anchorages free to move in two dimensions in a plane, a hack-saw blade mounted between said anchorages and having set teeth and a back, a work holder, means for reciprocating the anchorages together in one dimension in the plane relatively to the work-holder, a guide support of less width than the overall set of the saw teeth constrained against movement relative to the work-holder in that one dimension but movable relatively to the work-holder in the other dimension in the plane and rigidly supported to bear against the back of the hack-saw blade, and means for feeding the guide support in that other dimension towards the work-holder.

2. A hack-saw machine comprising saw anchorages free to move in two dimensions in a plane, a hack-saw blade mounted between said anchorages and having set teeth and a back, a work-holder, means for reciprocating the anchorages together in one dimension in the plane relatively to the work-holder, a guide support of less width than the overall set of the saw teeth constrained against movement relative to the work-holder in that one dimension but movable relatively to the work-holder in the other dimension in the plane and rigidly supported to bear against the back of the hack-saw blade, pairs of lateral guides, rigidly secured to the guide support, the guides of each pair being located on and bearing against opposite sides of the hack-saw blade clear of the set teeth thereof, the pairs being spaced apart longitudinally of the blade, and means for feeding the guide support in that other dimension towards the work-holder.

3. A hack-saw machine comprising saw anchorages free to move in two dimensions in a plane, a tapered hack-saw blade mounted thereon and having set teeth and a smooth back, the distance between the line of the teeth and the smooth back being less at the leading end of the blade in the cutting direction than at the trailing end of the blade, a work-holder, means for reciprocating the anchorages in one dimension in the plane relatively to the work holder, a guide support of less width than the set of the saw teeth constrained against movement relative to the work-holder in that one dimension but movable relative to the work-holder in the other dimension in the plane and rigidly supported to bear against the smooth back of the hack-saw blade, and means operable near the commencement of a working stroke in the reciprocation of the anchorages for irreversibly feeding the guide

support in that other dimension towards the work-holder.

4. A hack-saw machine comprising saw anchorages free to move in two dimensions in a plane, a hack-saw blade mounted between said anchorages and having set teeth and a back, a work-holder, means for reciprocating the anchorages together in one dimension in the plane relatively to the work-holder, a guide support of less width than the overall set of the saw teeth constrained against movement relative to the work-holder in that one dimension but movable relatively to the work-holder in the other dimension in the plane and rigidly supported to bear against the back of the hack-saw blade, an irreversible screw and nut mechanism effectively connected between the guide support and the work-holder, and means for relatively rotating the components of said mechanism.

20 5. A hack-saw machine comprising saw anchorages free to move in two dimensions in a plane, a hack-saw blade mounted between said anchorages and having set teeth and a back, a work-holder, means for reciprocating the anchorages together in one dimension in the plane relatively to the work-holder, a guide support of less width than the overall set of the saw teeth constrained against movement relative to the work-holder in that one dimension but movable relatively to the work-holder in the other dimension in the plane and rigidly supported to bear against the back of the hack-saw blade, an irreversible screw and nut mechanism effectively connected between the guide support and the work-holder, and frictional means governed by the means for reciprocating the anchorages for applying a limited turning moment to one of the components of said mechanism.

6. A hack-saw machine comprising saw anchorages free to move in two dimensions in a plane, a hack-saw blade mounted between said anchorages and having set teeth and a back, a work-holder, means for reciprocating the anchorages together in one dimension in the plane relatively to the work-holder, a guide support of less width than the overall set of the saw teeth constrained against movement relative to the work-holder in that one dimension but movable relatively to the work-holder in the other dimension in the plane and rigidly supported to bear against the back of the hack-saw blade, an irreversible screw and nut mechanism effectively connected between the guide support and the work-holder, and a friction clutch having one component connected with one of the components of the screw and nut mechanism and adapted to apply a turning moment thereto, and means governed by the means for reciprocating the anchorages for rotating the other component of the friction clutch.

7. A hack saw machine comprising saw anchorages free to move in two dimensions in a plane, a hack saw blade mounted between said anchorages and having teeth and a back, a work holder, means for reciprocating the anchorages together in one dimension of the plane relatively to the work holder, a guide support situated between the locuses of the blade ends, constrained against movement relatively to the work holder in that one dimension but movable relatively to the work holder in the other dimension and rigidly supported to bear against the back of the hack saw blade, and means for feeding the guide support in that other dimension.

8. A hack saw machine comprising saw anchor-

ages free to move in two dimensions in a plane, a hack saw blade mounted between said anchorages and having teeth and a back, a work holder, means for reciprocating the anchorages together in one dimension of the plane relatively to the work holder, a guide support situated between the locuses of the blade ends, constrained against movement relatively to the work holder in that one dimension but movable relatively to the work holder in the other dimension and rigidly supported to bear against the back of the hack saw blade, pairs of lateral guides rigidly secured to the guide support, the guides of each pair being located on and bearing against opposite sides of the hack saw blade between the locuses of the ends thereof, the pairs being spaced apart longitudinally of the blade, and means for feeding the guide support in that other dimension towards the work holder.

9. A hack saw machine comprising a work holder and a relatively movable straight guide adapted to be moved to or from the work holder in a direction substantially perpendicular to its length, saw anchorages reciprocable only parallel with said straight guide and, a tapered hack saw blade mounted on said saw anchorages with its back parallel to said straight guide, reciprocating means for reciprocating said saw anchorages, a guide support between the locuses of said saw anchorages rigidly connected to said straight guide and bearing against the back of the saw blade, an irreversible feed mechanism interconnecting the straight guide and the work holder and operating means for the irreversible feed mechanism interconnected with said reciprocating means and adapted to maintain said irreversible feed mechanism stationary during the cutting stroke of the machine and to operate it in a step during every cycle so as to advance the straight guide in a step.

10. A hack saw machine comprising saw anchorages free to move in two dimensions of a plane, a tapered hack saw blade mounted thereon and having teeth and a smooth back, the distance between the line of the teeth and the smooth back being less at the leading end of the blade in the cutting direction than at the trailing end of the blade, a work holder, means for reciprocating the anchorages in one dimension in the plane relatively to the work holder, a guide support situated between the locuses of the blade ends, constrained against movement relatively to the work holder in that one dimension but movable relatively to the work holder in the other dimension in the plane and rigidly supported to bear against the smooth back of the hack saw blade, and means operable near the commencement of a working stroke in the reciprocation of the anchorages for irreversibly feeding the guide support in that other dimension.

11. A hack saw machine comprising saw anchorages free to move in two dimensions in a plane, a hack saw blade mounted between said anchorages and having teeth and a back, a work holder, means for reciprocating the anchorages together in one dimension in the plane relatively to the work holder, a guide support constrained against movement relative to the work holder in that one dimension but movable relatively to the work holder in the other dimension in the plane and rigidly supported to bear against the back of the hack saw blade, an irreversible screw and nut mechanism effectively connected between the guide support and the work holder and means

for relatively rotating the components of said mechanism.

12. A hack saw machine comprising saw anchorages free to move in two dimensions in a plane, a hack saw blade mounted between said anchorages and having teeth and a smooth back, a work holder, means for reciprocating the anchorages and blade together in one dimension in the plane relatively to the work holder, a guide support situated between the locuses of the blade ends, constrained against movement relative to the work holder in that one dimension but movable relatively to the work holder in the other dimension in the plane and rigidly supported to bear against the back of the hack saw blade, an irreversible screw and nut mechanism effectively connected between the guide support and the work holder, and means for relatively rotating the components of said mechanism.

13. A hack saw machine comprising saw anchorages free to move in two dimensions in a plane, a tapered hack saw blade mounted between said anchorages and having teeth and a smooth back, the distance between the line of the teeth and the smooth back being less at the leading end of the blade in the cutting direction than at the trailing end of the blade, a work holder, means for reciprocating the anchorages together with the blade in one dimension in the plane relatively to the work holder, a guide support situated between the locuses of the blade ends, constrained against movement relatively to the work holder in that one dimension but movable relatively to the work holder in the other dimension in the plane and rigidly supported to bear against the smooth back of the hack saw blade, an irreversible screw and nut mechanism effectively connected between the guide support and the work holder and means for relatively rotating the components of said mechanism in a step at each cycle of operation.

14. A hack saw machine comprising a work holder and a relatively movable feed arm having a straight guide adapted to be moved to or from the work holder in a direction substantially perpendicular to its length, saw anchorages reciprocable only parallel with said straight guide and adapted to receive a hack saw blade, reciprocating means for reciprocating said saw anchorages, rigid brackets depending from said feed arm between the locuses of the saw anchorages, a guide support parallel to said straight guide rigidly clamped to said brackets and adapted to bear against the back of a saw blade held by said saw anchorages and means for applying a substantial load to the feed arm.

15. A hack saw machine comprising a work holder and a relatively movable feed arm having a straight guide adapted to be moved to or from the work holder in a direction substantially perpendicular to its length, saw anchorages reciprocable only parallel with said straight guide, a tapered hack saw blade mounted on said saw anchorages with its back parallel to said straight guide such that, as the blade is traversed in the cutting direction successive teeth move in paths which are successively nearer to the work holder, reciprocating means for reciprocating said saw anchorages, rigid brackets depending from said feed arm between the locuses of the saw anchorages, a guide support parallel to said straight guide rigidly clamped to said brackets and bearing against the back of the saw blade, means for maintaining said feed arm stationary in relation

to the work holder during the cutting stroke of the machine and means for advancing the feed arm in a step during every cycle.

16. A hack saw blade comprising an elongated tapered strip of metal, adapted to be secured under tension at its ends in a hack saw machine, narrower at one end than at the other and having a straight smooth surface along one of its longer mutually inclined sides adapted to be reciprocated in contact with and in relation to a fixed guide support and a single series of cutting

5 saw teeth extending substantially along the whole length of the other of said sides, the tips of said saw teeth lying in a line which is inclined to said straight smooth surface, said saw teeth each presenting a cutting face towards the narrower end of the blade and a sloping relief, oblique to the length of the blade, towards the broader end of the blade.

GEORGE SWAIN.
WILLIAM LESLIE BOWER.
